MOLDED TRAY FOR A BADMINTON SET OR THE LIKE

Ajit Singh, 179 Sawmill Road,
Scarsdale, N.Y. 10583

Filed July 7, 1967, Ser. No. 8,118

Term of patent 3½ years

(Cl. D9—185)

The figure is an isometric view of a molded tray for a badminton set or the like showing my new design.

The side walls, the bottom and the one end wall not disclosed in the drawing are each of planar rectangular configuration and unornamented.

I claim:

The ornamental design for a molded tray for a badminton set or the like, as shown and described.
